DRESSER OR THE LIKE

Warren C. Church, Hurt, Va., assignor to The Lane Company, Inc., Altavista, Va., a corporation of Virginia

Application December 5, 1958, Serial No. 53,664

Term of patent 14 years

(Cl. D33—6)

Fig. 1.

Fig. 2.

The essential features of the design are shown in the drawing in solid lines.

The back or rear of the dresser or the like (not shown in the drawing) is plain and unornamented.

The left hand side of the dresser or the like (not shown in the drawing) is plain and unornamented, and will be similar in appearance to the right hand side of the dresser or the like, as is customary.

I claim:

The ornamental design for a dresser or the like, as shown and described.
